UNITED STATES PATENT OFFICE.

HERBERT L. THOMPSON, OF NEWTON, IOWA, ASSIGNOR TO THE MAYTAG COMPANY,
OF NEWTON, IOWA, A CORPORATION OF IOWA.

SPARK CONTROL AND GOVERNOR FOR INTERNAL-COMBUSTION ENGINES.

1,343,943.

Specification of Letters Patent. Patented June 22, 1920.

Application filed May 10, 1916. Serial No. 98,518.

To all whom it may concern:

Be it known that I, HERBERT L. THOMPSON, a citizen of the United States, residing at Newton, in the county of Jasper and 5 State of Iowa, have invented new and useful Improvements in Spark Controls and Governors for Internal-Combustion Engines, of which the following is a specification.

10 This invention relates to spark controls for internal combustion engines, and particularly to an automatic, self adjusting spark control therefor, adapted to perfectly control the advancement or retardation of 15 the spark as the speed of the engine varies, and also to automatically throw the spark off when the engine overspeeds.

It is an object of the invention to provide an apparatus of the class described, in 20 which the centrifugal force generated by the revolution of a part of the engine is availed of to automatically control the advancement or retardation of the spark, and whereby this same force is employed to interrupt the 25 spark entirely if the engine should overspeed.

It is a further object of my invention to make the mechanisms for carrying out the results just mentioned, adjustable so as to 30 perfectly control the operation of the engine.

In the drawings, Figure 1 is an elevation of an engine constructed according to my invention.

35 Fig. 2 is a sectional view on line 2—2 of Fig. 3.

Fig. 3 is a detailed side elevation, partly in section of the spark control.

Fig. 4 is a top plan view thereof.

40 The invention is shown as applied to a 2-cycle engine, but it is to be understood that it is equally applicable to 4-cycle, or other, engines.

Fig. 5 is a transverse sectional view showing the mounting of the fly wheel.

1 represents the crank shaft of an internal combustion engine. Journaled upon the shank 6, sleeved upon the shaft 1 extending from the engine casing is the rotary fly 50 wheel 2, driven by a pin connection from the end of the crank shaft 1, as clearly shown in Fig. 5. The rotary fly wheel 2 is provided with fan blades 3, the particular engine herein disclosed being air cooled.

55 Firmly mounted upon the shank 6, rigid

with the engine casing, is the stationary commutator 7, secured to the shank 6 by means of the set screw 8, and provided with a contact plate 9, secured therein by the short screw 10. Screw 10 affords a connection for the insulated lead wire 11, of an electric circuit provided with a battery. The lead wire 11 goes to the battery, while the wire from the battery is grounded on the engine, and therefore on the commutator 65 brush hereinafter described, as will be readily understood. One of the fan blades 3 is provided with a stud or pin 12, projecting toward the engine therefrom, upon which is pivotally mounted a bent arm comprising an upper portion 13 and a lower portion 14, at an angle thereto, the portion 14 at its outer end being provided with a bearing pin 15, upon which, in turn, is pivotally mounted a bent arm, having at its inner end the weight 16, provided with a stop lug 16', adapted to rest against the arm 14, and at its outer end with a contact finger 17. The arm 13 is connected at its upper end by a spring 18 to a stud 19 on the fan blade 3. 70 75 80

Upon the arm 14, and in approximate alinement with the portion 17 is an extension 20, in which is adjustably mounted a screw 21, against the inner end of which the weight 16 is adapted to impinge upon certain contingencies to be described.

The operation of the device is as follows:—

When the engine is running the pin 12 carrying the spark control mechanism (13—20) 90 will be rapidly revolved. Under the influence of the spring 18, the bent arm 13 will be rocked so as to spread the joint between the contact arm 17 and the arm 14, while the centrifugal force of the weight 16 will have an opposite effect, tending to cause contact 17 to creep up the commutator, and thus advance the spark. The result of these combined forces will be that the contact 17 floats in just the right position for every speed of 100 the engine, advancing when the speed goes up and being retarded when the speed of the engine lags, this result being particularly aided by the fact that the spring increases in its effective force upon the arm 13 105 as it is stretched.

The device is also so constructed as to interrupt the spark altogether when the speed of the engine passes the limit for which it is set. This is accomplished by 110

the screw 21, against which the weight 16 impinges when the speed of the engine reaches a predetermined point, any increase thereafter in engine speed causing the arm 5 14 to be rocked about its pivot 12 in a contra-clockwise direction (see Fig. 2), carrying the contact 17 entirely clear of the commutator. It is obvious that the maximum speed of the engine may thus be accurately 10 adjusted by means of the screw 21.

I claim—

1. In an internal combustion engine, a stationary commutator, a rotating brush revolving about said commutator, and centrifugally operated means to retard or advance the brush according to the speed of the engine, whereby the spark is controlled automatically.

2. In an internal combustion engine, a stationary commutator, a rotary contact therefor revolving thereabout, comprising a pair of arms pivotally connected together and having sliding engagement with said commutator, centrifugally operated means 25 to cause one of said arms to move relatively to the other, whereby the contact will be advanced or retarded and the spark thus automatically controlled.

3. In an internal combustion engine, a stationary commutator, a brush revolving about said commutator, and centrifugally operated means carried by said brush to retard or advance the brush according to the speed of the engine to automatically control 35 the spark.

4. In an internal combustion engine, a stationary commutator, an arm adapted to rotate about said commutator, a lever pivotally mounted on said arm, and a brush 40 pivotally connected to said lever and carrying a weight at one end whereby to centrifugally control the spark.

5. In an internal combustion engine, a stationary commutator, an arm adapted to 45 rotate about said commutator, a lever pivotally mounted on said arm, a brush pivotally connected to said lever and carrying a weight at one end whereby to centrifugally control the spark, and means to limit the movement of said brush circumferentially of said commutator.

6. In an internal combustion engine, a stationary commutator, a rotary contact therefor revolving thereabout, comprising a 55 pair of arms pivotally connected together, centrifugally operated means to cause one of said arms to move relatively to the other, whereby the contact will be advanced or retarded and the spark thus automatically controlled, and in combination with adjustable means whereby the contact is raised off the commutator at a predetermined speed of the engine.

7. In an internal combustion engine, a 60 commutator, an arm adapted to rotate about

said commutator, a lever pivotally mounted on said arm, a second lever pivotally connected to the first lever and terminating in a commutator contact, a weight connected with the second lever, resilient means to 70 force said contact against said commutator, whereby the centrifugal force generated by the revolution of said arm, acting in opposition to the effect of said spring, will cause said contact to advance or lag with respect 75 to said commutator, substantially as described.

8. In apparatus of the class described, a stationary disk having a conducting portion and a non-conducting portion, a rotary support adjacent to said disk, a jointed arm pivotally mounted on said rotary support, and having at one end sliding contact with said disk, and means comprising a resilient member acting in opposition to centrifugal force for causing said jointed arm to be 80 slidably advanced or retarded with relation to said disk as the speed of rotation of said arm changes.

9. In apparatus of the class described, a 90 crank shaft, commutator, a rotary support upon the crank shaft, a jointed arm, comprising two sections, one thereof pivotally mounted on the support, and the other thereof pivoted intermediate its ends on the 95 first and terminating at one end in a contact slidably engaging the commutator and at the other in a weight, the joint of said jointed arm spreading under increased rotational speed of said support, resilient means 100 acting upon the first arm, normally tending to close said joint as said speed decreases, whereby the contact will advance or lag with respect to its position on the commutator, according to the speed of the engine. 105

10. In apparatus of the class described, a crank shaft, commutator, a rotary support upon the crank shaft, a jointed arm pivotally mounted on the support and slidably bearing at one end on the commutator, a 110 point angularly displaced from the pivotal support of said arm, resilient means acting upon said arm, normally tending to close said joint, and centrifugally operating means operating to spread said joint. 115

11. In apparatus of the class described, a crank shaft, a commutator disk, a rotary support driven by the crank shaft, a jointed member pivoted to the rotary support and bearing at one end on the commutator, 120 resilient means and weight operated means to control the relative position of the contact of said jointed member with the commutator and means for causing the contact with the commutator to be broken for over speeding 125 of the engine.

12. In apparatus of the class described, a crank shaft, commutator, a rotary support upon the crank shaft, a jointed arm, comprising two sections, one thereof pivotally 130

mounted on the support, and the other thereof pivoted intermediate its ends on the first and terminating at one end in a contact for the commutator and at the other in a weight, the first section being extended to form a stop to limit the motion of the second section about its pivot in one direction, resilient means acting on the first section, all so constructed and arranged that the contact with the commutator and thereby the spark will be advanced or retarded according to engine speed, and upon excessive engine speed the commutator and arm will be separated.

13. In an internal combustion engine, a contact device, a rotary support, an arm pivoted on said support but eccentrically

with respect thereto, a second arm pivoted to and carried by one end of said first arm, a weight on one end of said second arm and 20 a contact device on the other end thereof, whereby the relative movement of the two arms under the influence of the centrifugal force generated by the weight will cause the contact device on the end of the second 25 arm to be shifted with relation to the first mentioned contact device.

In witness whereof I hereunto subscribe my name to this specification in the presence of two witnesses.

HERBERT L. THOMPSON.
